(57) **CLAIM**

The ornamental design for a 3D geared tripod head, as shown and described.

DESCRIPTION

FIG. 1 is a front, top perspective view of a 3D geared tripod head showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, bottom perspective view thereof;

FIG. 9 is an enlarged detail view taken from portion 9 of FIG. 1;

FIG. 10 is an enlarged detail view taken from portion 10 of FIG. 1; and,

FIG. 11 is an enlarged detail view taken from portion 11 of FIG. 8.

The broken lines represent a boundary for the purposes of disclosing areas of enlargement and form no part of the claimed design.
